UNITED STATES PATENT OFFICE.

CHARLES DE LUKACSEVICS, OF WEST NUTLEY, NEW JERSEY, ASSIGNOR TO WILLIAM H. DANE, OF EAST ORANGE, NEW JERSEY.

MACHINE FOR PRINTING PHOTOGRAPHIC PAPER.

1,123,131.

Specification of Letters Patent.

Patented Dec. 29, 1914.

Application filed September 7, 1911. Serial No. 648,159.

To all whom it may concern:

Be it known that I, CHARLES DE LUKACSEVICS, a citizen of the United States, residing at West Nutley, in the county of Essex and State of New Jersey, have invented new and useful Improvements in Machines for Printing Photographic Paper, of which the following is a specification.

The present invention relates to improvements in apparatus for printing photographic papers and materials, and particularly blueprint paper, and it has for its object primarily to provide a generally improved machine which may be operated economically and with facility.

A subsidiary object of the invention is to provide exposing mechanism for an apparatus of this kind which insures uniform distribution of the light during the printing operation, causing all portions of the resulting print to be of the same tone or exposure, the exposing mechanism preferably embodying arc lamps which are mounted on a hinged or movable carrier whereby these lamps may be readily shifted to operative printing position, and they may be readily moved into an inoperative position, thereby rendering the lamps freely accessible for cleaning, adjustment, and renewal of the carbons or electrodes, and while the exposing mechanism is in inoperative position, the transparent surface which the sensitized web passes is freely accessible for cleaning purposes.

Further objects of the invention are to provide improved and efficient tension and guiding means for insuring proper passage of the sensitized web with respect to the exposing apparatus; to provide a compensating and winding roller for rolling the web, which will allow for the increasing diameter of the roll of material and to provide means for readily adjusting the relative movement of the web through the machine.

To these and other ends, the invention consists of certain improved combinations and arrangements of parts, all of which will be hereinafter more fully described, the features of novelty being pointed out particularly in the claims at the end of the specification.

In the accompanying drawings, Figure 1 is a side elevation of a machine constructed in accordance with one embodiment of the

invention, and adapted to carry out the objects before described; Fig. 2 represents a front elevation partly in section, of the right hand side of the machine as viewed from the left in Fig. 1, part of the machine being broken away; Fig. 3 is a view similar to Fig. 2, showing in elevation the left hand side of the machine as viewed from the right in Fig. 1, parts of the machine being broken away; Fig. 4 represents a transverse section of the machine immediately above the exposing mechanism and on the line 4-4 of Fig. 5, parts being broken away and omitted for clearness; Fig. 5 represents an interior vertical section of the exposing mechanism and related devices on the line 5-5 of Fig. 4; Fig. 6 is a detail top plan view of the automatic tension and guiding rollers for the belts which feed the sensitized web past the exposing mechanism.

Similar parts are designated by the same reference characters in the several views.

The accompanying drawing shows one embodiment of the invention, and in this form of the invention the machine is especially adapted for use in the printing of blueprint paper. It will be understood, however, that the invention is not restricted necessarily to this particular use, but that it may be used for the printing of photographic papers of different kinds, and that modifications and changes may be made in the detail construction and the relative arrangement of parts, in order that the invention may be applied to the best advantage according to the requirements of each particular case.

In the present instance, the machine comprises generally a pair of upright side frames 1 and 2, which may be of flanged or rigid construction, as shown, in order to afford the necessary or desired rigidity. The side frames are connected at the top by angle irons 3 and 4; at the bottom by angle irons 5 and 6; and at the back by T-shaped cross bars 7 and 8.

The side frames of the machine are formed with segmental or substantially semicircular portions 22, which receive and support a similarly shaped glass or transparent medium 23, the ends of the latter resting upon strips of asbestos or similar yieldable material 24, which are interposed between the glass and the side frames of the machine to avoid breakage or stress upon the glass. A

2

pair of front and rear guide rollers 25 and 26 are mounted at opposite sides of the glass 23, which forms the wall of an exposing chamber, the guiding rollers being properly journaled in the two side frames of the machine. A plurality of belts 27 pass over the driving rollers 25 and 26 and lap around the convex surface presented by the under side of the glass or transparent medium 23.

10 The present invention provides means for efficiently tensioning and guiding these belts, in order that the web of sensitized paper may be evenly and properly fed around the glass. In the present instance, such means 15 comprises a shaft 28, the opposite ends of which are fixed in the side frames of the machine, and this shaft has two sets of guiding and tensioning rollers 29 and 30 mounted thereon. Each of these rollers is flanged, 20 for the purpose of guiding the belts and preventing lateral shifting or interference between the belts, the rollers being staggered and the flanges of the rollers at one side of the shaft being in substantial alignment with 25 the flanges of the rollers at the opposite side of the shaft. Each roller is mounted in a yoke shaped frame 31, having hubs 32 which are loosely engaged on the shaft 28, and each of these frames has an arm 33 which 30 receives one end of a tension spring 34, one end of each spring being attached to a relatively fixed cross bar 35. The alternate belts 27 coöperate with the set of tension rollers 29, while the remaining belts coöperate 35 with the tension rollers 30, these tension rollers having individual springs which operate at all times to draw the respective tension rollers downwardly and thereby maintain proper tension upon the belts.

40 The driving rollers 25 and 26 are provided with stud shafts 37 and 38, which coöperate with ball bearings 39 and 40 in the side frame 2 of the machine, and these stud shafts of the two rollers have sprocket 45 wheels 41 and 42 fixed thereon, these two sprocket wheels being connected by an endless chain 43 which serves to insure uniform rotation of the two feed rollers. The said shaft 38 of the driving roller 26 also has a 50 worm wheel 44 fixed thereto, and a worm 45 coöperates with this worm wheel to rotate the same. The worm 45 is fixed to a shaft 46, the latter being mounted in bearings formed on a suitable bracket 47, and the 55 lower end of the shaft 46 is connected by a universal joint 48 to a variable speed driving shaft 49, the latter being formed with an axially extending key way 50. The lower end of the shaft 49 is mounted in a suitable 60 bearing 51, and this bearing 51 is acted on by a compression spring 52, this compression spring being contained within a suitable housing 53 which is fixed to the frame of the machine and is provided with a set screw 65 54, the set screw coöoperating with the spring for varying the power or compression thereof, for a purpose that will be hereinafter described. The shaft 49 is provided with a wheel 55, the hubs 56 of which are mounted to slide axially of the shaft 49, and these 70 hubs are provided with keys 56^a which operate in the key way 50 of the shaft 49 and thereby form a spline connection which insures the rotation of the wheel 55 and the shaft 49 in unison, and also permits axial 75 shifting of the wheel 55 with respect to the shaft 49. The wheel 55 is preferably provided with a tire 57 of leather, rubber or other material having the necessary coefficient of friction, and this tire of the wheel 80 55 coöperates with a driving disk 58, the axial adjustment of the wheel 55 with respect to the center or axis of rotation of the disk 58 enabling the ratio of transmission 85 and consequently the relative speed of the wheel 55 to be varied. The disk 58 is mounted in the side frame 2 of the machine by an antifriction bearing 59, which is fixed to turn with the disk 58, and the disk is grooved to receive a belt 61 which is driven by a 90 pulley 62 on the shaft of an electric or other motor 63.

Axial shifting of the wheel 55 is accomplished by a slide 64 which is operative longitudinally on a pair of stationary guides 65, this slide having a grooved lug 64^a which coöperates with the wheel 55, and as the slide 64 is shifted longitudinally of the guides 65, the wheel will be adjusted axially of the shaft 49. Shifting of the slide 64 is accomplished in the present instance by a pin 66 which is fixed to the slide and operates in a slot 67 formed in one end of the adjusting lever 68, the latter being pivoted on the side frame of the machine at 69, and having 105 a rocking dog 70 which is adapted to coöperate with different portions of a toothed sector 71 which is fixed to the machine frame for the rocking of the adjusting lever 68, obviously shifting the wheel 55 with respect to the axis of rotation of the disk 58, and consequently varying the speed of rotation of the shaft 49 and the driving rollers 25 and 26 which are operated thereby. The compression spring 52 operates upon the 110 shaft 49 to press the tire of the wheel 55 in proper engagement with the disk 58.

The exposing mechanism, according to the present invention, insures uniform distribution of the light throughout the extent of 115 the sensitized surface during the printing operation, and this exposing mechanism is so constructed that it may be readily moved into operative and inoperative position, the exposing mechanism while in inoperative 120 position rendering the arc lamps or illuminating medium conveniently accessible and thereby enabling the other parts of the exposing mechanism to be reached and cleaned. In the present instance, this exposing mecha- 125 130

nism comprises a frame 72 which is preferably composed of channeled iron, to afford the desired rigidity and to form a pair of roller guides 73 and 74. The frame 72 is connected to the side frames 1 and 2 of the machine by pivots 75, so that the frame of the exposing mechanism is hinged to swing on a horizontal axis. A suitable number of properly placed illuminating devices 76 are provided, arc lamps being usually employed. These lamps are mounted on a carriage which embodies a part 77 which is contained within the frame 72 and is supported thereon by a suitable number of rollers 78. The rollers 78 operate longitudinally on the upper sides of the roller guides 73 and 74 of the frame 72 to permit the carriage 77 and the arc lamps thereon to be shifted longitudinally of the frame 72 and longitudinally of the curved glass 23. In the present instance, the carbons or electrodes of the arc lamps are inclosed within glass globes 80, and these globes are suspended from the carriage 77 by springs or hangers 81 in such a way that the globes can be removed for the cleaning of the lamps and the renewal or adjustment of the electrodes. During the printing operation the carriage and the lamps thereon are shifted to and fro on the frame 72, preferably through a distance equal to the distance between two adjacent lamps, for the purpose of distributing the light uniformly and thereby insuring a uniform tone or exposure to the prints. Different mechanisms may be employed for shifting the carriage to produce this result. In the present instance, a pair of springs 82 are provided, the outer ends of which are attached to one end of the frame 72, and the inner ends of the springs are attached to the reciprocating carriage 77, and a cord or chain 83 is detachably connected to the opposite end of the reciprocating carriage 77, this cord or chain passing over an idler roller 84 and being connected to the slide 85, the latter reciprocating in the stationary guides 86, and the slide is connected to a pitman 87, the pitman being operated by a crank 88 which is fixed to the shaft 37 of the driving roller 25. As the driving roller 25 revolves, reciprocating motion will be imparted to the slide 85, and this reciprocating motion of the slide will be transmitted by the cord or chain 83 to the carriage 77, thereby transmitting a to and fro motion to the carriage. The exposing mechanism, which embodies the reciprocating carriage and its carrier frame 72, is held in operative position by thumb screw 89, and is held in inoperative position by a similar set screw 90, Fig. 1 showing the exposing mechanism in inoperative position and Figs. 4 and 5 showing this mechanism in operative position. The carriage 77 is preferably covered and protected by a hood, composed of con-

vergently arranged members 91 and 92 which are rigidly connected at the top by a cross member 93 which is preferably of channel form, to insure the necessary rigidity. The winding roller 94 is mounted in fixed bearings above the driving roller 25, this winding roller having a slot 94^a adapted to receive the inner end of the web before the beginning of the winding operation, and the winding roller is operated from the driving roller 25 by a friction drive which will compensate for the increasing diameter of the roll of material thereon, as the winding operation proceeds, thereby enabling the winding roller 94 to operate without interfering with the feeding of the web at uniform speed by the driving rollers 25 and 26. In the present instance, the rollers 25 and 94 are provided with grooved pulleys 92^a and 93^a respectively, which are connected by a friction driving belt 94', this belt sliding upon the pulleys when the web accumulates upon the winding roller. The winding roller is adapted to wind over the printed web in the form of a continuous or uncut strip. However, in some cases it is desirable to feed the web from the machine without winding it upon the roller 94. For this purpose a table is provided which is composed of a stationary section 95 and an adjustable section 96, which is hinged to the stationary section 95 at 97. The adjustable section 96 of the table may be set in upright position and held in such position by a thumb screw 98, as shown in Fig. 1, at which time it cooperates with the stationary section 95 to form a receptacle to receive the web; or the adjusting section may be placed in a position in alignment with the section 95, as shown in Fig. 5. In each case it forms a table to support the material while being cut in suitable lengths. To facilitate the cutting of the web into proper lengths, a slotted plate 99 is inserted in the face of the table section 95, so as to enable a knife to be drawn across the web while resting in the slotted plate, for the purpose of severing the web. An adjustable gage 100 is also attached to the outer end of the adjustable table section 96, and by setting this gage properly, the web may be cut in lengths or sections of any desired size.

The roll of prepared paper is mounted on the shaft 128, each end of this shaft being supported by a bracket 129 which is fixed to the upper portion of the machine, the rear ends of this bracket being formed with notches 130 to receive a suitable number of cross ribs 131 which may serve to suspend the washed prints before effecting the drying thereof. The paper upon the roller of the shaft 128 may then be passed through the exposing mechanism, as in the instance just described.

The fan or blower 132 is preferably

5 mounted within a housing 133 at one side of the machine and in substantial alignment with the exposing mechanism, this fan being driven by a shaft 134 which is journaled in the housing and is provided with a pulley 135 which is driven by a belt 136, which cooperates with the driving pulley 137 of the shaft of the motor 63.

10 The negatives from which the prints are to be made are introduced between the sensitized material and the glass guide or support, and the negatives and the sensitized material are fed in unison beneath the glass support by the traveling belts, and during 15 this operation, the necessary exposure and printing is accomplished.

Having fully described my invention, I claim:

20 1. In an apparatus of the character described, the combination of a relatively stationary transparent medium, exposing means associated therewith, and means for feeding a web of material past said stationary medium embodying a plurality of traveling belts arranged to cooperate with the web and press it against said medium and flanged rollers guiding and tensioning said belts independently.

25 2. In an apparatus of the character described, the combination of exposing mechanism embodying a relatively stationary guide for a web of material, a plurality of traveling web-feeding belts arranged to engage the web and press it against said guide, and independently acting flanged rollers individual to said belts for guiding and tensioning them.

30 3. In an apparatus of the character described, the combination of exposing mechanism embodying a relatively stationary curved guide, a plurality of feeding belts lapsing said guide and arranged in immediate edgewise relation, and flanged tensioning and guiding rollers arranged in alternating relation, one of the tensioning devices 35 being individual to each belt.

40 4. In an apparatus of the character described, the combination of exposing mechanism embodying a relatively stationary guide, driving rollers arranged in parallelism at opposite sides thereof, a plurality of web-feeding belts passing over said rollers and cooperative with said guide, and independently acting flanged tensioning rollers individual to and cooperative with said belts to maintain uniform tension thereon.

45 5. In an apparatus of the character described, the combination of a guide, exposing means cooperative therewith, a plurality of individual belts cooperative with said guide and arranged in immediate edgewise relation for feeding a web past said guide, a shaft, a plurality of sets of flanged guiding and tension rollers pivotally mounted on 55 said shaft, one roller being cooperative with

each belt, and a tension device individual to and cooperative with each roller.

6. In an apparatus of the character described, the combination of a transparent curved guide, exposing means adjacent thereto, driving rollers mounted in parallelism at opposite sides of said guide, means for driving said rollers in unison, a plurality of belts cooperative with said driving rollers and movable past said guide, and flanged rollers for individually guiding and tensioning said belts.

7. In an apparatus of the character described, the combination of a curved guide for a sensitized medium and exposing means embodying illuminating devices, and a carrier pivoted at one side relatively to said guide for moving said devices to and from an operative position coincident with the axis of curvature of said guide.

8. In an apparatus of the character described, the combination of a curved transparent guide or support for a sensitized medium, and exposing means embodying a carrier pivoted at one side relatively to said guide and arranged to swing to and from an operative position coincident with the axis of curvature of said guide.

9. In an apparatus of the character described, the combination of a curved transparent guide or support for a sensitized medium, exposing means embodying illuminating devices arranged coincidentally with the axis of curvature of said guide, and a frame pivoted at one side relatively to said guide or support and supporting the exposing means, said frame being operative to carry the same into an inoperative position to render the illuminating devices accessible.

10. In an apparatus of the character described, the combination of a curved guide or support for a sensitized medium, exposing means embodying arc lamps adapted to occupy a position in cooperative relation with said guide and coincident with the axis of said curvature thereof, and a carrier frame pivoted at one side relatively to said guide or support and supporting the exposing means and operative to carry the latter into a position to render such means accessible.

11. In an apparatus of the character described, the combination of a curved guide or support for a sensitized medium, exposing means therefor embodying illuminating devices located coincidentally with the axis of curvature of said guide, a carrier frame supporting the exposing means and pivoted at one side relatively to said guide or support to carry the same into an operative or an inoperative position relatively to the guide, and devices for holding the carrier frame in either of such positions.

12. In an apparatus of the character de-

- scribed, the combination of a guide or support for a sensitized medium, means for feeding such medium past said support, exposing means adjacent to said guide and reciprocable relatively thereto, and means operative by said feeding means for reciprocating the exposing means to produce uniform exposure of the sensitized medium.
13. In a machine for printing sensitized material, the combination of a curved transparent support for the sensitized medium, means for feeding such medium past said support, exposing means arranged within and mounted to reciprocate longitudinally of said support, and means operative by said feeding means for regularly reciprocating said exposing means.
14. In a machine for printing sensitized material, the combination of a support for positioning the sensitized material, means for feeding such material relatively to said support, exposing means, a traveling carriage supporting the exposing means, and means operative by said feeding means for reciprocating the exposing means regularly during the exposing operation.
15. In a machine for printing photographic material, the combination of a curved transparent support for positioning the material, means for feeding such material past said support, a carriage reciprocable axially of said support, exposing means mounted on said carriage and reciprocable thereby within said support, and means operative by said feeding means for reciprocating the carriage regularly during the exposing operation.
16. In an apparatus of the character described, the combination of a transparent support for positioning a sensitized medium in exposing position, means for feeding a sensitized medium past said support, exposing means having a carriage coöperative with and reciprocable relatively to said support, and means operative by said feeding means for reciprocating the carriage and exposing means.
17. In an apparatus of the character described, the combination of a support for positioning a sensitized medium for exposure, a carriage reciprocable relatively to said support, exposing means carried by said carriage and movable therewith, a spring for moving said carriage in one direction and means for moving the carriage in a reverse direction.
18. In an apparatus of the character described, the combination of a support for positioning a sensitized medium for exposure, exposing means coöperative with and movable in parallelism relatively to said support, and a carrier frame having said exposing means movably mounted thereon and shiftable to carry the same to and from operative position relatively to said support.
19. In an apparatus of the character described, the combination of exposing mechanism embodying a guide, means for feeding a sensitized web of material past said guide and exposing and printing upon said web, a table arranged at the delivery of said feeding means, a gage forming an upstanding stop on said table for the web, and a severing device on the table spaced from and coöperative with said gage.
- In testimony whereof I have hereunto set my hand in presence of two subscribing witnesses.
